UNITED STATES PATENT OFFICE.

FRANCIS J. TORRANCE, OF ALLEGHENY, PENNSYLVANIA.

DESIGN FOR A WASHSTAND.

SPECIFICATION forming part of Design No. 24,851, dated November 5, 1895.

Application filed October 3, 1895. Serial No. 564,556. Term of patent 14 years.

To all whom it may concern:

Be it known that I, FRANCIS J. TORRANCE, citizen of the United States, residing at Allegheny, in the county of Allegheny and State of Pennsylvania, have invented and produced a new and original Design for Washstands; and I do hereby declare the following to be a full, clear, and exact description of the invention, such as will enable others skilled in the art to which it appertains to make and use the same.

My invention has relation to designs for washstands, and relates in particular to a design for the slab and bowl of a washstand.

In the accompanying drawings, Figure 1 is a perspective view, Fig. 2 a plan view, and Fig. 3 a vertical sectional view, of a washstand-bowl and slabs embodying my design.

In the said drawings, A designates the bowl, which is elliptical in plan view and is surrounded by the horizontal slab B, the front

half of which is of semielliptical form, being concentric to the bowl A, while the two sides C C and the rear edge of the slab are straight.

The slab B has a raised portion b extending around the front and along both sides, which raised portion joins the flat portions B' of the slab by a rounded or ogee curve b', while the bowl joins the flat portion of the slab by a rounded edge c. At the back of 30 the slab is a vertical wall slab D, having the rounded upper edge d.

Having described my invention, I claim—

The design for a wash stand herein shown and described.

In testimony whereof I affix my signature in presence of two witnesses.

FRANCIS J. TORRANCE.
